UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS OF AND APPARATUS FOR CONVERTING HEAVY INTO LIGHTER HYDROCARBONS

Continuation of application Serial No. 266,397, filed December 12, 1918. This application filed May 2, 1923, Serial No. 636,103. Renewed May 28, 1928.

This application is a continuation of an earlier application filed by me, under date of December 12, 1918, Serial No. 266,397.

This invention relates to improvements in converting heavy into lighter hydrocarbons and refers more particularly to a continuous process in which the oil is fed through a heating zone into a vapor zone, the vapors taken off and the heavier ones condensed and returned to the heating zone. In this connection, one of the objects of the invention is to provide a process in which gas pockets are prevented from forming in the heating zone and in general to provide an improved process of the character referred to.

In the drawings:

Fig. 1 is a fragmentary side elevation of the apparatus.

Fig. 2 is an end elevation of the same.

Fig. 3 is a sectional plan view.

Referring in detail to the drawings, in a furnace construction 1, are mounted two sets of coils 2 and 3, the coil 2 being the heating coil and in the heating zone, and the coil 3 forming the vapor chamber or in other words, being in the vapor zone. The oil is delivered by means of delivery pipe 4 to the heating coil 2 and entering the pipe as shown at 5. The oil passes through the heating coil and then out through connecting pipe 6 to the vapor coil 3. The unconverted residue is drawn off from the larger coil by means of line 7 to a residuum tank. This line 7 is controlled by valve 8. The vapors pass up from the ends of the coil 3 through risers 9 and 10 which are connected to the respective ends of the coils through manifolds 11 and 12. The upper ends of the risers are connected by horizontal pipes 13 and 14 to downwardly inclined pipes 15, 16, 17 and 18. The delivery end of these pipes 15, 16, 17 and 18 are connected to a tank 19 and are controlled by valves 20. The tank 19 is connected at its upper side with pipes 21 forming an aerial condenser 21a, which in turn is connected to a water condenser through pipe 22. The water condenser (not shown) has its outlet side equipped with a throttle valve for maintaining a back pressure of the vapors on the entire system but inasmuch as the idea of

having a valve on the outlet side of the condenser to control the pressure on both the still and the condenser is well known in the art, it need not be here shown or described.

The heavy vapors which condense and collect in tank 19 are returned to the heating zone for re-treatment through pipe 23 and in which is interposed a pump 23a. The pipe 23 is connected to the inlet coil as shown at 23b. Gas is supplied to the burners by means of line 24 and branch lines 25.

The oil is subjected to treatment at a temperature in excess of 500 degs. F., in the heating zone and a pressure of 50 pounds or more is preferably maintained in the entire system.

As an important feature of the invention, the process is so operated as to prevent pocketing of gas in the heating zone. To this end, in the line 6 is interposed a pressure valve 26 which is set to open at a predetermined pressure which is slightly less than the operating pressure used. If the pressure in the vapor lines falls, vapor cannot back up into the heating zone. In this way, vapor is prevented from returning from the vapor chamber or zone to the heating zone.

I claim as my invention:

1. A continuous process for cracking hydrocarbon oil, consisting in passing the oil in a confined stream through a heating zone wherein the oil is subjected to a conversion temperature, in discharging the heated oil into an elongated vaporizing zone, in discharging vapors progressively from said vaporizing zone as the oil passes therethrough, in combining the progressively withdrawn vapors, in subjecting them to a dephlegmating action, in returning the reflux condensate under a mechanical pressure to the heating zone for re-treatment, in continuously withdrawing unvaporized residual oil from said vaporizing zone to be isolated from the system, in normally maintaining a uniform regulated superatmospheric pressure on the oil throughout the process and in maintaining constant the pressure on the oil in the heating zone in the event of a temporary decrease in pressure on the oil in the remaining zones of the process.

2. An apparatus for cracking hydrocarbon

oil, comprising an elongated heating coil disposed within a furnace, an elongated horizontally disposed vaporizing zone, a communication from said heating coil to said vaporizing zone, means for withdrawing vapors from said vaporizing zone at points progressively arranged from the liquid inlet to said zone to the liquid outlet thereof, means for dephlegmating the vapors withdrawn from said vaporizing zone, means for returning the reflux condensate resulting from said dephlegmation of the vapors to the heating coil, means for condensing the dephlegmated vapors, means for collecting the resulting distillate, means for normally maintaining a uniform superatmospheric pressure throughout the apparatus, and means positioned in the communication from said heating coil to said elongated vaporizing zone for preventing a decrease in pressure occurring in the vaporizing zone from being communicated to the heating coil, and means for withdrawing unvaporized oil from the liquid outlet of said vaporizing zone to be isolated from the system.
